Fig. 3.

Des. 217,751

PAGE 3

Fig. 4.

Fig. 5.

FIG. 1 is a side perspective view of a masonry saw showing by new design;

FIG. 2 is a perspective view showing the opposite side thereof;

FIG. 3 is a front perspective view thereof showing that side of the masonry saw illustrated in FIG. 2;

FIG. 4 is a rear perspective view showing a portion of that side of the masonry saw illustrated in FIG. 1; and

FIG. 5 is a fragmentary top perspective view showing a portion of that side of the masonry saw illustrated in FIG. 1.

Portions appearing in dotted line are for illustrative purposes only and form no part of my present design.

I claim:

The ornamental design for a masonry saw, as shown.
